UNITED STATES PATENT OFFICE

ROBERT N. FALGE, OF DETROIT, MICHIGAN, ASSIGNOR TO GENERAL MOTORS RESEARCH CORPORATION, OF DETROIT, MICHIGAN, A CORPORATION OF DELAWARE

HEAD LAMP

Application filed October 29, 1927. Serial No. 229,684.

This invention relates to a headlight for an automotive vehicle.

In headlights with which I am familiar it has been the practice to form either a shelf 5 or a shallow annular groove in the rim or flange of the reflector and glue a gasket of cork or cotton cord or similar material on this shelf or groove in position to contact the lens, thus providing a sealing cushion between the reflector and lens. The process of manufacture of reflectors is such that only a shallow groove can be formed for the cord, so shallow that the cord is easily pulled out of its seat and the seal broken. A particular 10 disadvantage of the cork gasket is that it tends to become brittle and often breaks when the lens is removed to change the bulb in the headlight or make some other adjustment or repair.

It is an object of this invention to provide a headlight with a new and improved sealing connection between the reflector and lens. It is a further object of the invention to provide an improved gasket for use in this connection, using the less expensive materials available for such purposes. It is a further object of the invention to so construct the adjacent portions of the rim and lens that my improved gasket will be held in place when the lens is removed for changing the bulb.

Other objects and advantages of the invention will appear in the course of the following description, taken in connection with the accompanying drawing and appended 35 claim.

In the drawing:

Figure 1 is a rear view of a separate lens constructed to conform with my invention;

Figure 2 is a section on the line 2-2 of 40 Figure 1;

Figure 3 is a vertical longitudinal section through the upper portion of an assembled headlight embodying my invention; and

Figure 4 is an enlarged detail view, partly 45 broken away, of a modified form of gasket cord.

Referring to Figure 3 of the drawing, I have illustrated a portion of a concavo-convex reflector 10 which is provided with an 50 annular rim 12, which extends outward in a

plane perpendicular to the axis of the reflector. The outer portion of the rim is recessed at intervals to provide countersunk portions 14 apertured for reception of fastening screws 16.

The numeral 18 indicates a bullet shaped casing, though my invention is not limited to any particular shape of headlight. Fitting within the rim of the casing is the annular body band 20, fixed within the casing in any 60 usual way, such as by welding. The body band 20 is bent inward slightly to form an annular shoulder 21, then extends forward and then inward, as at 23, in a plane perpendicular to the axis of the casing 18. At this 65 point the band 20 extends rearward and inward, as at 25, to provide a support for reflector 10.

A number of threaded apertures are provided in the portion 23 of the band for receiving the respective screws 16 for adjustably positioning the reflector 10 relative to the casing 18.

The lens, as shown in Figures 1 and 2, comprises a glass disc 24 provided with the usual corrugations, though my invention is equally applicable with a headlight comprising a fluted reflector and a plain lens. The lens is formed on the inner side with a groove 26 which is substantially semi-circular in 75 cross section. The groove extends completely about the lens except for a small plain segment 27 at the lower part. Held within the groove and forming a sealing cushion 80 between the lens and reflector, as shown in 85 Figure 3, is the gasket 30.

The gasket comprises an ordinary closely woven cotton cord. The gasket may or may not be glued into place. The cord rests on the surface of the rim 12 of the reflector 90 and is compressed slightly when the lens is fixed firmly in position in the assembled headlight.

The means for holding the lens in position comprises the door ring 34 the outer surface 95 of which conforms to the outer surface of casing 18. It may be noted that the front side of the lens is shaped adjacent the rim to provide an annular groove 36, and the door ring is provided with an inward extend-

- ing flange 38 which is crimped rearward slightly to fit within groove 36. Within the door ring is a reinforcing ring 40, which conforms roughly to the shape of the door ring 34. Reinforcing ring 40 is provided with an inward extending flange 42 which follows the contour of the door ring flange 38 and contacts with the forward side of the lens adjacent groove 36. The axially extending portion of reinforcing ring 40 is bent outward to contact with door ring 34 as illustrated and extends flush with the edge of the door ring where the ring 40 abuts against the annular shoulder 21 of the body band 20.
- 15 The door ring 34 is held snugly against casing 18 by any usual or desirable fastening means (not shown).

With the construction just described, the flange on the reflector may be comparatively narrow as the cord gasket is quite narrow and the fastening screws are partially countersunk in the edge of the flange. In prior constructions it has been the practice to extend this flange outward a short distance, then bend it rearward and outward for providing a seat for a comparatively large cork gasket. The flange must extend out some distance still farther beyond the gasket in order to provide a hole for reception of the fastening screw. My invention makes it feasible to provide a flange on the reflector which is narrower than the flange of the conventional reflector by an amount slightly greater than the width of the cork gasket commonly used. Thus with my invention a larger reflector may be used for a given size of casing. This permits the door ring to be narrower and makes possible a better and more desirable design of headlamp. These results are obtained by forming the groove 36 in the lens, which may be readily accomplished. Production conditions are such with the reflector that only a shallow groove in the rim of the reflector is practicable.

45 In Figure 4 I have illustrated a modified and more expensive form of cord gasket. This comprises a helical steel wire 50, such as a piano wire, over which is drawn a cover or sleeve 52 which may be of thin cotton fabric. This form retains its shape a little better than the plain cotton core and tends to remain more firmly seated in the groove 26 in the lens. It also permits greater commercial variations in the spacing between 55 lens and reflector where the latter is fastened to the shoulder on the housing and thereby avoids poor sealing, on the one hand, and, on the other, distorted doors.

I claim:

- 60 An automobile headlamp comprising a casing, a reflector in the casing, a lens fitted over the reflector and provided with a peripheral groove for receiving a sealing gasket, a gasket in the groove, said reflector being provided with a narrow outturned flange having

a plane surface adapted to engage the sealing gasket throughout substantially its entire length to prevent entrance of dust and moisture, said flange being provided with discontinuous countersunk portions outwardly of the line of contact with said gasket, means 70 engaging said countersunk portions and the casing for securing the reflector to the casing, and means for clamping the lens to the reflector and casing.

75 In testimony whereof I affix my signature.

ROBERT N. FALGE.
